UNITED STATES PATENT OFFICE.

HARRY GERARD LEOPOLD, OF CINCINNATI, OHIO.

ROTARY MOTOR.

No. 834,819.

Specification of Letters Patent.

Patented Oct. 30, 1906.

Application filed October 4, 1905. Serial No. 281,366.

To all whom it may concern:

Be it known that I, HARRY GERARD LEOPOLD, lieutenant-commander United States Navy, and a citizen of the United States, residing at Cincinnati, in the county of Hamilton and State of Ohio, have invented certain new and useful Improvements in Rotary Motors, Pumps, &c.; and I do hereby declare the following to be a full, clear, and exact description of the invention, such as will enable others skilled in the art to which it appertains to make and use the same.

This invention relates to improvements in rotary engines and motors, and may be employed in connection with a rotary steam or other fluid-operated engine, internal-combustion gas-engines, rotary pumps, pressure-fans, water-motors, &c.

One of the objects of the invention is to eccentrically mount a revoluble disk or support within an annular casing, said disk or support being provided with a plurality of foldable pistons around its peripheral surface adapted to be moved during their cycle of operation from their folded or collapsed position to their open or distended position, the free ends of the pistons bearing against the annular casing or an interior lining therefor to prevent leakage therearound.

Other objects and advantages will appear from the following specification, and the particular features of novelty will be pointed out in the claims.

To more fully describe the invention, reference is had to the accompanying drawings, illustrating an application of same, in which—

Figure 1 is a side elevation of a rotary engine, motor, or pump embodying an application of the invention. Fig. 2 is a horizontal section on the line 2 2 of Fig. 3. Fig. 3 is a vertical section through the casing and shaft, the interior working parts being shown in elevation, with one of the pistons in section for the purpose of illustration. Fig. 4 is a detached perspective view of one of the pistons. Fig. 5 is a similar view showing another method of packing the side walls of the piston. Fig. 6 is a fragmentary view, in horizontal section, substantially similar to Fig. 2, but showing a slightly-modified construction; and Fig. 7 is a fragmentary sectional view showing a further modification in the application of an insert member or dutchman for the interior of the casing between the inlet and exhaust openings.

Referring to Figs. 1 to 3 for the purpose of

illustration, the casing is shown as comprising the annular side plate 1, the laterally-extending peripheral web 2, and the annular flange 3, to which latter is bolted, as shown, or otherwise suitably secured the opposite side plate 4, forming the inclosing chamber for the working parts.

Integral with the outside faces of the annular side plates 1 and 4 and disposed eccentrically thereon are the journal-bearings 5, strengthened by the bracing-webs 6 and provided with the usual boxes or brasses 7, in which is journaled the shaft 8. The apertures for the shaft 8 in the side plates 1 and 4 are of such a diameter with reference to the bearings 5 that there is formed an interior annular shoulder 9, against which the brasses 7 abut on one side and on the other side abuts the central enlargement 8^a on the shaft 8, 10 designating annular bosses on the inside faces of the side plates 1 and 4, the whole forming a compact mounting for the shaft when the side plates 1 and 4 are assembled. These side plates 1 and 4 are also provided on their outer faces with the annular bosses 11, which permit the inside faces of the side plates to be annularly recessed, as at 12, for a purpose hereinafter referred to.

The casing is also provided with the inlet-port 13 and outlet-port 14, formed on the peripheral web 2, and this peripheral web is braced and supported by the rear vertical web 2^a, the forward web 2^b, and the base-plate or support 2^c, all formed integral with the side plate 1.

15 is a wheel-support or disk carried by the shaft 8, and consequently mounted eccentrically with reference to the annular cylinder or casing, and this wheel-support or disk is provided on its peripheral surface with foldably-mounted pistons adapted to be collapsed and distended during their cycle of operation.

While by the term "foldable pistons" it is intended to cover any form of a piston which may be flexed into position against the inside face of the casing, it is preferable in actual construction to pivotally secure or hinge detachably-mounted pistons to the peripheral surface of the wheel-support or disk. To this end 16 designates the pistons, which are of scoop or pan shape, as clearly shown in Fig. 4, 16^a designating the concave impact-face, and 16^b the side plates thereof, which terminate in the solid cylindrical rear portion 16^c, adapted to be inserted into socket mem-

bers 17, extending laterally of the wheel support or disk 15. These socket members are sufficiently deep to prevent the cylindrical portion 16^e from being displaced when the 5 various parts are in their assembled position; but it will be readily observed that the pistons may be connected to the wheel-support by sliding the cylindrical portion 16^e laterally into the socket members 17.

10 The outer faces of the pistons 16^b are grooved to receive a suitable packing 16^d, adapted to contact on inside faces of the side walls of the cylinder to prevent leakage.

15 18 designates a lining for the cylinder, of hard steel, which is cut away and tapered to fit around the inlet and exhaust openings, as clearly illustrated.

Leakage alongside the disk or rotary support 15 is prevented by means of an annular 20 packing-ring 19, of asbestos or other suitable material, inserted in the annular recesses 12 of the casing, (see Fig. 2,) and these packing-rings 19 may be set up against an annulus 20, formed on each side of the wheel-support 15, 25 the packing being held in direct contact therewith by any suitable means, such as set-screws, augmented by suitable springs 21, mounted within the recesses 12 between the casing-walls and the packing-rings. It is

30 obvious, however, that any suitable way of interposing packing between the rotary support and the casing may be employed, the foregoing being principally for the purpose of illustration.

35 The operating fluid is prevented from seeking its way from the inlet to the exhaust except in the desired direction by so mounting the disk or wheel-support that the peripheral surface of same will lie adjacent the cylinder-casing, at the top thereof, and by continuing the inner face of the web 2 of the casing, as at 2^d, Fig. 3, concentric with the wheel-support or disk 15, forming an arc or ledge at the joinder of the inlet-port with the 40 web 2 sufficient to effectually prevent the passage of the working fluid in a reverse direction. This is augmented by originally machining the inner surface of the casing or lining therefor, so that the curved outer faces

45 of the piston will form a snug contact therewith, or, as illustrated in Fig. 7, by interposing a machined piece or dutchman 22 along the inside of the casing between the inlet and the exhaust, or by fitting a spring-vane 23 adjacent the inlet or receiving nozzle in such 55 manner that the end of the spring-vane will project beyond and form a substantial continuation of the ledge 2^d.

In Fig. 5 is shown a slightly-modified form 60 of the piston provided with the water-grooves 16^e in the sides to act in place of packing.

In Fig. 6 is illustrated a slightly-modified construction in which the wheel-support or disk 15 is provided with side plates or disks 65 15^a, projecting beyond the wheel-support,

70 forming annular side rims 15^b, between which are disposed pistons, as heretofore described. In this construction the side disks 15^a are disposed in recesses 15^c, formed in the side plates of the casing, 15^d designating packing-rings interposed between the side plates of the wheel-support and the casing.

The operation is fairly apparent from the foregoing description and illustrations, but may be briefly referred to as follows:

75 When the machine is employed as an engine—for instance, as a rotary steam-engine—and the parts being in the position shown in Fig. 3, the introduction of the working fluid through the inlet-port 13 will 80 cause the fluid to impinge against the curved face 16^a of the piston and initially drive same forward by impact, and at the same time the charge of fluid between each pair of preceding pistons will be expanding therebetween 85 until the exhaust-port is reached, when they discharge therethrough. The same operation will be performed if an explosive mixture or charge was ignited behind the first piston in front of the inlet-port.

90 It will be obvious that when the machine is to be used as a rotary pump or blower, &c., power is applied to the shaft 18 and the direction of rotation of the pistons reversed.

95 While for the purpose of illustrating a practical application of the invention I have thus described the same, it will be understood that modifications might be made without departing from the spirit of the invention, and I do not, therefore, limit myself to the 100 precise details disclosed, but

96 What I claim is—

1. In an expansion rotary engine or motor, the combination with an annular casing, of a 105 rotary disk eccentrically mounted in said casing, a plurality of pistons hinged to said disk, said pistons comprising scoops or pans with flat sides and packing therefor and with outer edges adapted to register with the interior of the annular casing and having their free ends 110 adapted to swing and engage the interior of said casing, an inlet-pipe opening into the contracted portion of the passage between said disk and said casing, and an outlet-pipe opening outward from approximately the 115 broadest part of said passage, whereby a series of expansion-chambers between the pistons is secured, substantially as described.

2. In an expansion rotary engine or motor, the combination with an annular casing, of a 120 rotary disk eccentrically mounted in said casing, a plurality of pistons hinged to said disk, said pistons comprising scoops or pans with flat sides and packing therefor and with outer edges adapted to register with the interior of the annular casing and having their free ends 125 adapted to swing and engage the interior of said casing, an inlet-pipe opening tangentially into the contracted portion of the passage between said disk and said casing, and 130

an outlet-pipe opening outward from approximately the broadest part of said passage, whereby a series of expansion-chambers between the pistons is secured, substantially as described.

3. The combination with an annular casing having an inlet and an outlet, of a rotary support eccentrically mounted within said casing, a plurality of circumferentially-disposed foldable pistons carried by said support and a flexible vane adjacent said inlet and projecting in the path of rotation of said pistons, substantially as described.

4. The combination with an annular casing having an inlet and outlet and provided

with recessed side walls, of a rotary wheel-support, annular side plates for said wheel-support disposed in the annular recessed portion of said casing-plates, circumferentially-disposed foldable pistons carried by said wheel-support between said side plates, and packing-rings interposed between said side plates and casing, substantially as described.

In testimony whereof I affix my signature in presence of two witnesses.

HARRY GERARD LEOPOLD.
